UNITED STATES PATENT OFFICE.

GEORGE F. ELLIOTT, OF WASHINGTON, DISTRICT OF COLUMBIA.

BOTTLE-CLOSURE.

1,178,389.

Specification of Letters Patent. Patented Apr. 4, 1916.

Application filed November 23, 1915. Serial No. 63,092.

To all whom it may concern:

Be it known that I, GEORGE F. ELLIOTT, a citizen of the United States, residing at Washington, in the District of Columbia, have invented certain new and useful Improvements in Bottle-Closures; and I do hereby declare the following to be a full, clear, and exact description of the invention, such as will enable others skilled in the art to which it appertains to make and use the same.

My present invention relates to improvements in bottle closures, and it is especially intended to provide an improved bottle closure using a metal cap with an inner layer or layers of soft compressible material, and in which it is desired to use the minimum amount of metal possible to secure an efficient bottle closure.

My invention is especially intended to provide an improvement over the construction shown in my Patent No. 1,157,518, granted October 19, 1915, and entitled "Improvements in stoppers for bottles," and in my allowed application, Serial No. 28,367, filed May 15, 1915, and entitled "Improvements in bottle closures." According to my patent aforesaid a material saving in metal in the cap is effected by using a thin disk of resilient material in the cap, whereby a shallow cap may be used; while in my application, Serial No. 28,367, I effect a further saving in the metal of the cap by the form of tabbed construction therein shown. In both of those devices the blank from which the metal cap is formed is stamped out of a sheet plate, leaving considerable waste metal between the adjacent blanks; and the principal object of the present invention is to reduce this waste metal to a minimum.

It is well known that a continuous floor may be made of a series of blocks having square blocks, or hexagonal blocks all the blocks being of the same size, and that the blocks may be made to fit snugly together without the necessity of any intervening lining. In a similar way the body of a plate of sheet metal may be cut up into a series of similar squares or hexagons, with comparatively small waste of metal, and these blanks so cut from the sheet may be pressed into a series of cup-shaped caps adapted to fit over the neck of the bottle. It will be also seen that the hexagonal shape when so bent will provide a greater series of downwardly projecting tabs than the square, and

will require a smaller blank to accomplish the same result than if the blank were square.

According to my invention I cut an ordinary plate of sheet metal, such as is ordinarily used in the manufacture of metal caps for bottle closures, into a series of hexagonal blanks, and I force these blanks in a suitable die to a cup-shaped form; when they are provided with the usual lining disk or disks of suitable soft yielding material, and are then placed in position on the top of the bottle and are secured in place by a suitable die, as is well known in the art.

My invention will be more clearly understood by reference to the accompanying drawings, in which the same parts are indicated by the same reference symbols throughout the several views:

Figure 1 is a perspective view of the bottle top, showing my improved cap applied thereto; Fig. 2 shows a section along the line 2—2 of Fig. 1, being through two oppositely-disposed tabs of the metal cap; Fig. 3 shows a section along the line 3—3 of Fig. 1, being taken between two of the tabs of the cap; Fig. 4 shows the plate from which the blanks are cut, and the manner in which they are cut; Fig. 5 shows one of the blanks detached from the plate and ready for forming into the cup-shaped cap; and Fig. 6 shows a modification, in which a slightly larger blank is used, and with more rounded angles.

A represents the neck of the bottle having the usual bead *a* at the top thereof.

B represents the metal cap which in the finished shape is shown in Figs. 1, 2 and 3, and in which condition it is preferably provided with the indentation *b*, the tabs *b*² and the corrugated sides *b*³. Inclosed in this cap are one or more layers or disks of suitable material, such as cork, birch bark, corn stalk, or any other suitable yielding material.

In Fig. 5 one of the blanks from which the metal cap is formed is shown, which is hexagonal in shape having the sides *b*² with the angles slightly rounded as at *b*¹. This slight rounding of the angles is preferable for convenience in manipulating the bottle stopper, but does not interfere with the essential feature of the invention. A series of these blanks *B*⁰ are cut out of a plate *D*, as shown in Fig. 4, there being ordinarily a narrow zig-zag strip of metal *b*⁰ left be-

tween adjacent blanks in the process of cutting, for convenience in cutting the same and in rounding the angles b' , and this waste of metal in such cases is very small indeed.

In practice the blank B° is forced through a die to form a cap B, such as is shown in Figs. 1-3, and the angles b' are caused to form downwardly-projecting tabs symmetrically disposed to the cup-shaped cap; between which tabs a series of corrugations b^4 are formed. When the lining disks are placed in the cap, and the cap is inserted, a suitable tool is forced down over same, causing the lower edges of the cap to project into the groove beneath the bead a , and causing the two sides of the tab b^4 to form shoulders b^6 which will project into the groove beneath the bead a , as shown in Fig. 2. These tabs will thus not only form locking means for said cap, but will also project slightly from the sides of the bottle, as shown in Fig. 2, and may be conveniently gripped by a suitable tool for removing the cap as in the operation of opening the bottle.

By having the blanks B° formed hexagonal in shape, there will be six of the tabs b^4 and twelve locking shoulders b^6 , in addition to the six locking edges b^8 , as shown in Fig. 3, all of which, being symmetrically disposed around the bottle, will give a secure gripping effect to the cap when it is secured in place, as shown in Figs. 2 and 3. Moreover, by having the blanks hexagonal, and all of the same size, they may be cut out of a sheet of metal with very little loss of waste metal in the sheet.

In the form of device shown in Fig. 6, I have shown the angles of the hexagon cut away as at b'' , somewhat more than the angles of the hexagon are rounded, as shown at b' , in Fig. 5. This would give a somewhat wider space between the shoulders b^6

when the cap is mounted over and secured 45 on the bottle top.

Thus it will be seen that I provide a metal cap for bottle closures of the character described, in which the locking tabs are symmetrically disposed relative to the circumference of the cap, thus providing a substantially uniform holding effect throughout the circumference of the cap; and by having these caps formed from hexagonal blanks a cap of the maximum diameter is 55 used, with a minimum waste of metal in cutting the same from the sheets.

Having thus described my invention what I claim and desire to secure by Letters Patent of the United States is:—

1. A bottle closure comprising a metal cap formed from a blank substantially in the form of a regular hexagon, having its periphery bent downward to form a cup shape, the angles of the hexagon, being bent, to form a series of equidistant crimped tabs projecting beyond the main body of the cap, and shoulders formed on each side of each tab to engage beneath the bead of the bottle neck when compressed to the locking position, substantially as described.

2. A bottle closure comprising a metal cap formed from a blank substantially in the form of a regular hexagon, having its periphery bent downward to form a cup 75 shape, the angles of the hexagon, being bent, to form a series of equidistant crimped tabs projecting beyond the main body of the cap, and shoulders formed on each side of each tab to engage beneath the bead of the bottle 80 neck when compressed to the locking position, with yielding packing means mounted in said cup-shaped cap, substantially as described.

In testimony whereof, I affix my signature.

GEORGE F. ELLIOTT.
